FULL-LENGTH DOME OR DOUBLE-DECK RAILWAY CAR WITH NORMAL-HEIGHT END DOORS

Goodrich K. Murphy, New Canaan, Conn., assignor to The Budd Company, Philadelphia, Pa., a corporation of Pennsylvania

Application February 23, 1952, Serial No. 272,983

5 Claims. (Cl. 105—340)

1

The invention relates to a dome or double-deck railway car, and its aim is combining the advantages and overcoming the shortcomings of known comparable types of cars while keeping the dimensions within the clearance lines of the railroads.

One known type of car has a so-called dome or upper deck extending longitudinally over the mid-region only and adding little, if any, to the revenue space. It can be run between ordinary cars and has a passageway through them from car to car on the low-level floor.

Related to the aforesaid type of car is a known type of car, sometimes called a triple-deck car. This type has end portions over the truck at the height of normal cars, whereas between the trucks there are two decks—a lower deck below and an upper deck above the level of the end portion decks. This means a rather complicated arrangement and restricts the upper deck to the same relatively small region as in the type of car described in the preceding paragraph.

Still another known design has a full-length upper deck and a short lower deck restricted to the region between the trucks. The space between the low-level floor above the trucks and the high-level floor is less than standing height and is used for equipment and storage only. There is no passage through the car at the low-level. The end doors, if any, are connected by stairs with the upper deck, so that such passage from car to car requires climbing up and down stairs, which is evidently undesirable.

A car, designed in accordance with the invention, has an upper deck or dome of substantially the full length of the car, a lower deck or compartment restricted to the space between the trucks, and lateral passageways connecting the low-level floor with end doors at normal level, these passageways being arranged higher than the low-level floor so as to clear the trucks and extending upwardly beyond the high-level floor. The high-level floor has preferably a depressed center aisle, raised side portions carrying the seats and preferably providing room for upward extension of the lateral aisles.

Further objects, advantages, and features of the invention are disclosed or more fully explained in the following description of one embodiment which is illustrated in the attached drawing.

In the drawing:

Fig. 1 is a small scale, three-quarter side and front perspective of a complete railway car.

Fig. 2 is a somewhat diagrammatic side elevation of the same car.

2

Figs. 3 and 4 are sectional plan views taken along the correspondingly numbered lines of Fig. 2;

Fig. 5 is a fragmentary perspective, on a larger scale, certain parts being broken away and shown in section approximately along line 5—5 of Fig. 2;

Figs. 6, 7, and 8 are longitudinal, vertical, diagrammatic sections along the correspondingly numbered lines of Fig. 4; and

Figs. 9, 10, and 11 are vertical transverse, diagrammatic sections on a larger scale along the correspondingly numbered lines of Figs. 3 and 4.

The car body illustrated in the drawing is supported near its ends by trucks 15. Floor portions or decks 16, in the region over and adjacent the trucks, are at normal floor height of standard single-deck passenger cars. A passage or communicating door opening 17 in each end wall 18 is of standard dimensions and location so as to line up with corresponding doors in ordinary single-deck passenger cars, and leads to end vestibule 19.

A low-level floor or deck 20 is restricted to the space between the end trucks 15 and is at a level substantially below the level of the end decks 16. An upper deck or high-level floor 21 extends substantially the full length of the car; more accurately, it extends between the inner partition walls 22 of the vestibules 19, see particularly Fig. 8.

Decks 20 and 21 are spaced full standing height from each other so that deck 20 may be used for any desired purpose—revenue passenger space, club room, kitchen, sleeping facilities, rest rooms, etc.

The space between decks 16 and 21 is, however, as in certain known above-mentioned types of cars, of less than standing height and would appear usable only for storage, auxiliary machinery, and other equipment such as water tanks.

Upper deck 21 has over its full length a longitudinal center aisle 23 and raised side portions 24 supporting seats 25. The enclosed space 26 between the main portion of deck 21 and the raised portions 24 is, for most of the length of the car, available as air ducts or for similar purposes.

The spaces between decks 16 and upper deck 21 are separated from the space above lower deck 20 by transverse partitions 27 and are each divided by a longitudinal partition wall 28 into a compartment 29 for storage, machinery or equipment and an aisle 30 with staircase 31. These aisles connect with lower deck 20 by steps 32 and communicate with end vestibules 19. The

necessary standing height for the aisles is obtained by cutting with the aisles into the upper deck and closing them by horizontal partition walls or ceilings 33. Ducts 31' may extend across ceilings 33 (Fig. 11). In the region of the aisles, there is a row of single seats only instead of the double seats in the rest of the upper deck.

Staircases 31 and the sections of aisles 30 at the side of them are in open communication at the top with the space above the upper deck. This region is enclosed by half-height partitions and railings 34 leaving a passage opening between them.

The aisles 30 at opposite ends of the car are preferably arranged along opposite side walls 35. Entrance door 36 is provided for one vestibule 19 in one of the side walls.

The side walls 36 have window openings 37, and the transversely arched roof 38 has large curved windows 39 in its longitudinal sides and end windows or windshields 40 in its ends.

The roof end portions 41, between windows 40 and end walls 18, are of normal height and curvature so as to line up and blend in with cars of standard single-deck construction. The longitudinal central portion of the roof is formed as a duct 42 for air, wiring, lights, etc.

The compartments 29 over the truck locations are, of course, provided with access doors or hatches and, if desired, with windows. These optional features are not shown save for the louvers or vents 43 in Figs. 1, 2, and 3 to 5.

The constructional details of the new design may follow in large part the construction disclosed in copending application Railway Car, Serial No. 734,955, filed March 15, 1947, by inventors Walter B. Dean and Albert G. Dean, issued on March 18, 1952, under Patent No. 2,589,997.

A car according to the invention is, of course, more expensive than an ordinary coach car or a car with a short-length dome, as disclosed in the aforesaid application. In the final analysis, however, the expense for a train equipped with the new cars is about within the same range as the expense for a train composed of ordinary cars and a number of short-length dome cars.

The new design presents additional advantages.

Firstly.—For the short-length dome car, it was found desirable to maintain a certain ratio between non-revenue dome seats and seats at the normal level. In cars of the new design all seats at the high level may, of course, be revenue seats or a much smaller number of these dome cars may be used for a train of a certain length mainly composed of ordinary cars.

Secondly.—All dome or double-deck cars have the advantage that they give on the upper deck much quieter riding to the passengers because the space between the underframe and the high level floor acts as sound insulator. This very noticeable advantage becomes available to a much greater number of passengers in a car of the new design than in trains with a relatively small number of dome seats as afforded by the short-length dome cars interspersed in a majority of regular cars.

The invention is susceptible to modifications and adaptations without departing from its basic concept. For instance, the side aisles may be lowered one step with respect to the main portion of the floor above the trucks, in which case the side aisles would be connected by a

single step with the floor of the respective vestibule.

What is claimed is:

- 5 1. A railway car of cross-sectional dimensions keeping substantially within established clearance lines, comprising: end walls; side walls; a roof; normal-level floors, at about the floor level of customary single-deck passenger cars, in and adjacent the location of trucks for supporting the car; vestibules at the ends of the car provided with passage doors of standard height and dimensions in said end walls; a compartment with a low-level floor between said truck locations at a level below said normal-level floors; a high-level floor extending substantially over the full length of the car from the vestibule at the one end to the vestibule at the other end thereof, said high-level floor being at full standing height above said low-level floor, at less than standing height above said normal-level floors, and at full standing height below said roof; transverse partition walls interconnecting said side walls, said low-level floor and said high-level floor in the meeting regions of said normal-level floors and said low-level floor; longitudinal partitions spaced from one of said side walls and extending between said normal-level floors and said high-level floor and providing side aisles communicating with said vestibules and the compartment with the low-level floor, said side aisles projecting upwardly beyond the high-level floor by upward extensions of their longitudinal partition walls and by raised ceilings so as to provide full standing height in the side aisles; steps 10 connecting said side aisles with said low-level floor; at least one entrance door in one of the side walls such as at the location of one of said vestibules; and at least one stair leading to said high-level floor.
- 15 2. A railway car of cross-sectional dimensions keeping substantially within established clearance lines, comprising: end walls provided with passage doors of standard height and dimensions as to permit communication with adjoining ordinary single-deck cars; side walls; a roof; end floors, in and adjacent the location of trucks for supporting the car, at a level sufficient for clearing such trucks; vestibules at the ends of the car in communication with said passage doors; a compartment with a low-level floor between said truck locations at a level below said end floors; a high-level floor overlying said low-level floor and extending therebeyond in the longitudinal direction of the car, said high-level floor being at full standing height above said low-level floor but less than standing height above said end floors; transverse partition walls interconnecting said side walls, said low-level floor and said high-level floor in the meeting regions of said end floors and said low-level floor; longitudinal partitions spaced from one of said side walls and extending between said end floors and said high-level floor and providing side aisles communicating with said vestibules and the compartment with the low-level floor; said side aisles having projections extending upwardly beyond the high-level floor to full standing height; steps connecting said side aisles with said low-level floor; and at least one stair connecting one of said low-level and end floors with said high-level floor.
- 20 3. A railway car of cross-sectional dimensions keeping substantially within established clearance lines, comprising: end walls provided with passage doors of standard height and dimensions

as to permit communication with adjoining ordinary single-deck cars; side walls; a roof; end floors, in and adjacent the location of trucks for supporting the car, at a level sufficient for clearing such trucks; vestibules at the ends of the car in communication with said passage doors; a compartment with a low-level floor between said truck locations at a level below said end floors; a high-level floor overlying said low-level floor and extending therebeyond in the longitudinal direction of the car, said high-level floor being at full standing height above said low-level floor but less than standing height above said end floors; transverse partition walls interconnecting said side walls, said low-level floor and said high-level floor in the meeting regions of said end floors and said low-level floor; longitudinal partitions spaced from one of said side walls and extending between said end floors and said high-level floor and providing side aisles communicating with said vestibules and the compartment with the low-level floor; said side aisles having projections extending upwardly beyond the high-level floor to full standing height; steps connecting said side aisles with said low-level floor; said high-level floor having raised floor portions at the side of a central aisle, said raised portions providing room for air ducts and, at least in part, for the upward projections of said side aisles; and at least one stair connecting one of said low-level and end floors with said high-level floor.

4. A railway car of cross-sectional dimensions keeping substantially within established clearance lines, comprising: end walls provided with passage doors of standard height and dimensions as to permit communication with adjoining ordinary single-deck cars; side walls; a roof; end floors, in and adjacent the location of trucks for supporting the car, at a level sufficient for clearing such trucks, vestibules at the ends of the car in communication with said passage doors; a compartment with a low-level floor between said truck locations at a level below said end floors; a high-level floor overlying said low-level floor and extending therebeyond in the longitudinal direction of the car, said high-level floor being at full standing height above said low-level floor but less than standing height above said end floors; transverse partition walls interconnecting said side walls, said low-level floor and said high-level floor in the meeting regions of said end floors and said low-level floor; longitudinal partitions spaced from one of said side walls and extending between said end floors and said high-level floor and providing side aisles communicating with said vestibules and the compartment with the low-level floor; said side aisles

having projections extending upwardly beyond the high-level floor to full standing height; a single row of seats on said high-level floor between a center aisle thereon and said projections of said side aisles, and double rows of seats between said side walls and center aisle in regions remote from said side aisles; steps connecting said side aisles with said low-level floor; and at least one stair connecting one of said low-level and end floors with said high-level floor.

5. A railway car of cross-sectional dimensions keeping substantially within established clearance lines, comprising: end walls provided with passage doors of standard height and dimensions as to permit communication with adjoining ordinary single-deck cars; side walls; a roof; end floors in and adjacent the location of trucks for supporting the car at a level sufficient for clearing such trucks; vestibules at the ends of the car in communication with said passage doors; a compartment with a low-level floor between said truck locations at a level below said end floors; a high-level floor overlying said low-level floor and extending therebeyond in the longitudinal direction of the car, said high-level floor being at full standing height above said low-level floor but less than standing height above said end floors; transverse partition walls interconnecting said side walls, said low-level floor and said high-level floor in the meeting regions of said end floors and said low-level floor; longitudinal partitions spaced from one of said side walls and extending between said end floors and said high-level floor and providing side aisles communicating with said vestibules and the compartment with the low-level floor; said side aisles having projections extending upwardly beyond the high-level floor to full standing height; steps connecting said side aisles with said low-level floor; and stairs interconnecting said side aisles with said high-level floor being enclosed by partition walls forming a staircase, said stairs and staircase being arranged directly inwardly adjacent said side aisle.
